UNITED STATES PATENT OFFICE.

SPENCER LEROY MURPHY, OF WEST POINT, MISSISSIPPI.

WRENCH.

1,175,547.

Specification of Letters Patent.

Patented Mar. 14, 1916.

Application filed July 6, 1915. Serial No. 38,216.

To all whom it may concern:

Be it known that I, SPENCER L. MURPHY, a citizen of the United States, residing at West Point, in the county of Clay and State of Mississippi, have invented certain new and useful Improvements in Wrenches, of which the following is a specification, reference being had to the accompanying drawings.

10 My present invention relates to new and useful improvements in wrenches and as its principal object aims to improve tools of this character, particularly as regards the construction of the means by which the movable jaw of the wrench is held in adjusted position.

Another and more specific object of the invention is to provide a wrench embodying a shank, fixed jaw, a movable jaw and a holding mechanism for maintaining the movable jaw in adjusted position, which holding mechanism includes broadly a slide mounted upon the shank, a pawl pivoted in the slide and engageable with rack teeth upon the shank for holding the slide in adjusted position, and a means whereby the movable jaw may be further and more minutely adjusted after the slide has been initially adjusted.

30 The above, and other incidental objects of a similar nature, which will be herein-after more specifically treated are accomplished by such means as are illustrated in the accompanying drawings, described in the following specification, and then more particularly pointed out in the claims which are appended hereto and form part of this application.

With reference to the drawings, wherein 40 there has been illustrated the preferred embodiment of this invention, as it is reduced to practice, and throughout the several views of which similar reference numerals designate corresponding parts, Figure 1 is 45 a side elevation, of a wrench, the slide being shown in section; Fig. 2 is a section on the line 2—2, of Fig. 1; Fig. 3 is a side elevation of a modified form of a wrench, a portion of the side being broken away; Fig. 50 4 is a detail view illustrating the manner in which the two pawls of the modified form are associated; and Fig. 5 is a detail top plan view of the two pawls and adjoining parts of the wrench.

55 As embodied in the accompanying drawings and as best shown as an operative em-

tirety in Fig. 1 thereof, the wrench of the present invention includes as its essential elements, a shank 10 having an integral fixed jaw 11; a movable jaw 12; a slide 13, which is mounted on the shank, a pawl 14, by means of which the slide is held in adjusted position upon the shank, and a milled nut 15, by means of which the movable jaw may be further adjusted with respect to the element clamped by the wrench, after it has been initially adjusted by manipulation of the slide.

The shank 10 and fixed jaw 11 are formed in the usual and well known manner and 70 may be of any desired design. It is preferable that the shank be rectangular in cross section, in order that the yoke 16 of the movable jaw may be held against rotation on the shank. In this connection, it will be 75 obvious, however, that the shank may be hexagonal or any other desired cross section, except circular, without departing in any way from the spirit of the present invention. As shown in Fig. 1 particularly, 80 the yoke 16, which forms an integral part of the movable jaw 12, is disposed to embrace the shank 10 so that the movable jaw may be properly supported upon the shank for movement thereon toward and away 85 from the fixed jaw. Upon that face of the shank along which the movable jaw slides is formed, in the preferred embodiment of the tool, a longitudinal series of transversely disposed rack teeth, indicated 90 at 17. These teeth are engageable by the pawl 14 in a manner and for a reason which will be hereinafter fully explained.

The slide 13 is preferably formed in the nature of a single metallic casting and is 95 preferably rectangular in shape so that it may snugly embrace the shank 10 and, at the same time, slide thereon. The slide is held in adjusted position on the shank by means of the pawl heretofore designated by the numeral 14. This pawl is preferably formed as a wedge-shaped metal block, the lower end of which is adapted to move through a slot 18 formed in the top wall of a slide sleeve 13'. A pair of transversely 100 spaced, apertured ears 19 are formed integrally with the top of the slide sleeve and are arranged, as shown best in Fig. 1 to receive the pin or axle 20, upon which the arm 21 of the pawl 14 is pivoted. It will 105 be understood that the arm 21 may either be formed as an integral part of the pawl

or may be separately formed and secured thereto in any desired manner. A leaf spring, indicated at 22 is interposed between the pawl arm and the adjacent face of the 5 slide 13. This spring is disposed to bear against the outer end of the pawl arm so that the pawl will be normally held in engagement with the rack teeth 17, whereby the slide will be maintained against movement away from the fixed jaw 11. The 10 rear end of the pawl arm is shaped to form a thumb piece 23, so that the user of the wrench may easily and conveniently depress the rear end of the pawl arm to raise the 15 pawl and permit the further adjustment of the slide 13 upon the wrench shank.

In order that the slide sleeve 13' may be moved easily and without undue friction on the shank 10, this member is provided 20 on opposite sides of the toothed face with the longitudinal grooves 28, in which operate the anti-friction rollers 29. These rollers 29 are journaled upon an axle 30 and are seated within recesses 31 formed in the 25 shoulder 26, to be hereinafter described.

Referring now to Fig. 1 particularly, it will be seen that from the rear face of the movable jaw 12, there extends a stem or shank 24, which is threaded at its rear portion, as indicated at 25, to receive the milled adjusting nut 15. The nut 15 is arranged to abut against the forward face of a shoulder 26 which is preferably formed as an integral part of the slide member 13 and extends 30 at right angles thereto. Obviously, as will be seen best upon reference to Fig. 1, the nut may be turned to adjust the movable jaw 12, with respect to the slide member 13, after this member has been initially adjusted. 35

It now becomes apparent that it is necessary to provide some means for holding the adjusting nut 15 against lateral movement so that it may not become disengaged from 40 the shoulder 26. In this connection, I employ a sheet metal hook 27, which is carried by the shoulder 26. This hook as best shown in Fig. 1 receives the lower portion of the nut and serves to prevent the lateral movement of this member. I desire to explain, in 45 this connection, that while the hook member 27 in the preferred form of the invention, is employed to hold the nut against lateral movement, any other equivalent device or devices (such as lugs, projecting from the shoulder on opposite sides of the nut) may be substituted therefor, without departing 50 from the purview of this invention.

The actual construction and arrangement 55 of the several parts of the preferred form of the wrench, being thus described, it now remains to explain briefly the manner in which the movable jaw is adjusted with respect to the fixed jaw. In this connection, 60 reference will be had particularly to Fig. 1,

wherein it will be seen that the movable jaw 12 may be initially adjusted, by releasing the pawl 14 in the manner previously explained and adjusting the slide sleeve 13' longitudinally on the shank, to dispose the movable jaw at the approximate desired distance from the fixed jaw. By making the rack teeth 17 relatively small, the slide member 13 may, itself, be employed to adjust the movable jaw, by steps of one-eighth of an 75 inch, without making the teeth weak. If the adjustment of the movable jaw obtained by the adjustment of the slide 13, does not accomplish the desired, final adjustment of the movable jaw, this member may be further adjusted by manipulation of the adjusting nut 15, which has a range of adjustment 80 equal to the distance between the teeth 17.

When the wrench is to be employed with particularly small work of a character demanding that the movable jaw be quickly 85 adjusted to thirty-seconds of an inch, by merely sliding the member 13 on the wrench shank, I employ a modified structure as shown in Figs. 3, 4 and 5. As shown in 90 these figures, the shank is provided with two parallel longitudinal series of teeth 17^a and 17^b, the teeth of the one series being staggered with respect to the teeth of the other series. In the modified form of the 95 invention, the slide is provided with a pair of pawls 14^a and 14^b, instead of but one pawl, as in the preferred form. The pawl 14^a is disposed for engagement with the teeth 17^a, while the pawl 14^b is disposed for 100 engagement with the teeth 17^b. Thus, it will be seen that while the teeth are the same distance apart, as they are in the preferred form of the wrench, they are so arranged that the slide may be adjusted in spaces 105 which are one-thirtieth of an inch in length, even though the space between the teeth of each series is but one-sixteenth of an inch.

In reduction to practice, it has been found 110 that the form of this invention illustrated in the drawings, and referred to in the above description as the preferred embodiment, is the most efficient and practical; yet realizing that the conditions concurrent with the 115 adoption of this device will necessarily vary, it is desirable to emphasize the fact that various minor changes in the details of construction, proportion and arrangement of parts may be resorted to, when required, 120 without sacrificing any of the advantages of this invention, as defined by the appended claims.

What is claimed is:—

1. A wrench including a shank having a 125 fixed jaw, a movable jaw slidably mounted upon the shank, a slide embracing the shank and longitudinally movable thereon, rollers mounted upon the slide and engaging against the shank to hold that wall of 130

the slide upon which the rollers are mounted in spaced relation to the face of the shank, said face of the shank being provided with a longitudinally extending series of 5 rack teeth disposed between said rollers, a pawl mounted upon the slide adapted to engage the rack teeth to hold the slide in adjusted position, and means engaging the slide for shifting the movable jaw relative 10 to the slide but permitting the movable jaw to move with the slide.

2. A wrench including a shank having a fixed jaw, a movable jaw slidably mounted upon the shank, a slide embracing the shank 15 and movable therewith and having a laterally extending shoulder, the shank having rack teeth upon that face confronting the shoulder of the slide, rollers journaled in the slide and bearing against the shank on 20 each side of the rack teeth and holding that wall of the slide upon which the rollers are mounted in spaced relation to the teeth on the shank, a nut carried by the slide, the movable jaw having a screw threaded shank 25 engaging said nut, and a pawl carried by the slide and engageable with the rack teeth on the same.

3. In a wrench, a shank, a fixed jaw thereon, a movable jaw slidably mounted upon 30 the shank, one face of the shank being

formed with a medially disposed rib having rack teeth thereon, a slide mounted upon the shank, means mounted upon the slide and engaging the shank on each side of 35 said rack teeth and holding that portion of the slide which confronts the teeth in spaced relation thereto, means for engaging the teeth to hold the slide in adjusted position, and means on the slide for adjusting the movable jaw relative to the slide. 40

4. A wrench including a shank having a fixed jaw, a movable jaw slidable upon the shank, a slide movable on the shank, a shoulder extending at right angles to the slide, recesses formed in opposite sides of 45 the shoulder, rollers journaled in said recesses, the shank being provided on opposite edges with parallel longitudinal grooves, said rollers being disposed for movement through said grooves, means for holding the 50 slide in adjusted position upon the shank, and means connecting the shoulder and movable jaw.

In testimony whereof I hereunto affix my signature in the presence of two witnesses. 55
